[57] **CLAIM**

The ornamental design for a hanging egg shaped bunny ornament, as shown and described.

DESCRIPTION

FIG. 1 is a perspective view of a hanging egg-shaped bunny ornament showing my new design;

FIG. 2 is a front elevational view thereof;

FIG. 3 is a top plan view thereof;

FIG. 4 is a right side elevational view thereof, the left side being a mirror image;

FIG. 5 is a rear elevational view thereof;

FIG. 6 is a bottom plan view thereof;

FIG. 7 is a rear elevational view of second embodiment of FIG. 1, the difference residing in the rear being identical to the front;

FIG. 8 is a top plan view of FIG. 7;

FIG. 9 is a front perspective view of a third embodiment of FIG. 1, the difference residing in the position of the right ear;

FIG. 10 is a front elevational view of a fourth embodiment of FIG. 1, the difference residing in the modification of the face;

FIG. 11 is a front perspective view of a fifth embodiment of a hanging egg shaped bunny ornament with an opening feature showing my new design;

FIG. 12 is a right side elevational view of a fifth embodiment thereof, with the left side being a mirror image of the right side thereof;

FIG. 13 is a top plan view of a fifth embodiment thereof; and,

FIG. 14 is a bottom plan view of a fifth embodiment thereof.
